UNITED STATES PATENT OFFICE.

FRANK W. COLWELL, OF MATTEAWAN, NEW YORK.

DESIGN FOR A SPOON.

SPECIFICATION forming part of Design No. 36,147, dated November 25, 1902.

Application filed September 24, 1902, Serial No. 124,716. Term of patent 7 years.

To all whom it may concern:

Be it known that I, FRANK W. COLWELL, a citizen of the United States, residing at Matteawan, in the county of Dutchess and State 5 of New York, have invented and produced a new, original, and ornamental Design for a Spoon, of which the following is a specification.

This invention relates to spoons; and the 10 object thereof is to provide a design of this character that is new, original, and ornamental.

The accompanying drawing is a plan view 15 of the new design, the features of which reside in an ornamental handle and bowl, the latter containing in relief a view of Beacon Mountains, which are located at Matteawan, New York, together with the casino, inclined

railroad, depot, and power-house thereon. The handle is ornamenteally decorated and is 20 provided at the end opposite the bowl with a representation in relief of a monument located on the said Beacon Mountains.

Having thus described my invention, what I claim as new, and desire to secure by Letters 25 Patent, is—

The ornamental design for a spoon as herein shown and described.

In testimony that I claim the foregoing as my own I have hereto affixed my signature in 30 the presence of two witnesses.

FRANK W. COLWELL.
